UNITED STATES PATENT OFFICE.

SYLVESTER M. LOGAN, OF WARREN, OHIO; MILTON LOGAN, BEING EXECUTOR OF SAID SYLVESTER M. LOGAN, DECEASED, ASSIGNOR, BY DIRECT AND MESNE ASSIGNMENTS, OF ONE-HALF TO GERTRUDE M. NEYMAN, OF SHEAKLEYVILLE, PENNSYLVANIA, AND ONE-HALF TO MILTON LOGAN, OF WARREN, OHIO.

AEROPLANE.

1,413,670.

Specification of Letters Patent. Patented Apr. 25, 1922.

Application filed August 27, 1920. Serial No. 406,340.

To all whom it may concern:

Be it known that I, SYLVESTER M. LOGAN, a citizen of the United States, residing at Warren, in the county of Trumbull and 5 State of Ohio, have invented certain new and useful Improvements in Aeroplanes, of which the following is a specification.

My invention relates to an improvement in aeroplanes, and my object is to provide 10 an aeroplane which is particularly constructed to rise vertically from the ground, remain stationary in the air, move forward or backward at the will of the operator, and wherewith a landing may be accomplished 15 by slowly settling to the ground, all substantially as herein shown and described and more particularly pointed out in the claims.

In the drawings accompanying this application, Fig. 1 is a front view of my improved 20 aeroplane, Fig. 2 is a plan view, and Fig. 25 3 a side elevation, all said views being considerably reduced and diagrammatic. Fig. 4 is a plan view showing the detail construction of the propellers, and Fig. 5 is a side view thereof on the line of the counter-shaft.

As shown herein the invention has been applied to a bi-plane, and an opening 2 provided in the upper and lower planes centrally 30 between the ends thereof on the longitudinal median line of the body or main frame 3. Within this opening 2, or more correctly speaking, directly above this opening, I mount four horizontal propellers or 35 fans 4 on separate vertical shafts 5 having bevel gears 6 adapted to mesh with similar bevel gears 7 on a longitudinal counter shaft 8 situated centrally between twin motors 9 and 10 arranged at opposite sides of openings 2 between the two main planes. Each 40 motor has a forwardly-extending shaft 11 equipped with a driving propeller 12, and power is applied to counter shaft 8 from either motor shaft by separate sprocket 45 gears and chains 14 under the control of separate clutch devices 15, see Fig. 2. The lifting propellers 4 are also arranged in pairs revolving in opposite directions, and opening 2 is large enough to allow a free 50 passage for the air driven downward by the propellers 4. Any number of such lifting propellers may be used by using a line or

counter shaft 8 on the longitudinal median line of the body, and inasmuch as the lifting propellers revolve in opposite directions 55 they may be arranged closely together in quartered interlapping relation as shown.

The two fan blades of each lifting propeller 4 are also constructed to pivot or turn on a horizontal shaft 16 extending 60 through the vertical shaft 5 whereby the working angle of the blades may be changed by manipulating suitable levers 17 which are connected with the inner ends of the fan blades of propellers 4 by means of sliding 65 collars 18 and links 19, see Figs. 4 and 5. The driving propellers 12 also embody pivoted blades 20 linked to slidable collars 21 which are operatively controlled by pivoted levers 22 and 23 so that the working angle 70 of the blades may be changed or reversed to check the speed or reverse the travel of the aeroplane.

I also provide automatic shutters 24 directly underneath lifting propellers 4, see 75 Figs. 1 and 2, which will open when these propellers drive the air downward to raise the ship, and which shutters will close when the horizontal propellers 4 are idle and the ship is being driven forward by propellers 80 12. Partitions 25 are also provided under or opposite the lifting propellers or at the inner ends of the main planes to direct the air downwardly through the planes and prevent deflection and lifting resistance on 85 such planes. All of the propellers shown may be operated from either one of the engines alone in the event that the other engine becomes inoperative, thus assuring a continued flight and safe landing under 90 such conditions. The airship or plane may also be stabilized by changing the angle of the pivoted blades in the lifting wheels A and changing the angle of the shutters 24 beneath said lifting wheels. Operation of 95 shutters S may be effected by the pilot by means of levers 26 and cable connections 27, see Fig. 1.

What I claim is:

1. An aeroplane having main supporting 100 surfaces with an opening centrally on the longitudinal median line of the aeroplane, separate motors and driving propellers at opposite sides of said opening and line, a

series of horizontal lifting propellers arranged successively for reverse rotation on said line within said opening, and separate clutch drive connections between said motor and horizontal propellers.

- 5 2. An airship having a main supporting plane provided with an opening on the longitudinal center line of the ship, separate motors on opposite sides of said opening
10 and line, a counter-shaft on said line having power connections with both motors, a plural number of horizontal propellers centrally within said opening having power connection with said counter-shaft, and a

separate driving propeller connected with 15 each motor.

3. An aeroplane having a plural number of horizontal lifting propellers arranged in close interlapping relation successively on the longitudinal median line thereof, shutters beneath and deflecting partitions opposite said propellers, and means adapted to revolve the successive propellers in opposite directions.

Signed at Warren, in the county of Trumbull, and State of Ohio, this 21st day of August, 1920.

SYLVESTER M. LOGAN.
